UNITED STATES PATENT OFFICE.

FREDERIC PAYSON REED, OF EAST ORANGE, NEW JERSEY, ASSIGNOR, BY MESNE ASSIGNMENTS, TO CHARLES C. ORCUTT.

DRIER.

Application filed December 31, 1920, Serial No. 434,231. Renewed July 26, 1922. Serial No. 577,738.

To all whom it may concern:

Be it known that I, FREDERIC PAYSON REED, a citizen of the United States, residing at East Orange, in the county of Essex, State of New Jersey, have invented certain new and useful Improvements in Driers; and I do hereby declare the following to be a full, clear, and exact description of the invention, such as will enable others skilled in the art to which it appertains to make and use the same.

My invention is an improvement in driers for paper and the like in the web, and relates to that type of drier, wherein the web is dried by artificial heat, in a continuous operation.

An object of the invention is to provide electrically controlled means for heating and drying the web, over which the web is moved continuously, while so supported that it is under tension, to prevent buckling, warping and blistering.

Another object is to provide a support for the web, arranged to travel with the web, and to be moved at the speed of the web, and which will offer a minimum of impediment to the passage of the heat to the underside of the web.

Another object is to provide a support of such character that a relatively high temperature may be maintained in the heating means, without any danger of scorching or burning the web.

A further object is to provide an arrangement of heating and drying mechanism composed of one or more independent units, any number of which may be combined into a battery, and wherein each unit is complete in itself.

A further object is to provide a support so shaped as regards the web engaging portion that it will constrain the web to assume an arched formation longitudinally, as it travels with the support, whereby to hold the web taut and under tension to prevent warping, buckling or blistering.

In the drawings,

Figure 1 is a diagrammatic side view, showing the improved drier, in connection with the delivery end of a Fourdrinier machine, Fig. 2 is a partial vertical section of one of the units shown in Fig. 1, Fig. 3 is a section on the line 3-3 of Fig. 2, Fig. 4

is a plan view of a portion of the web support, Fig. 5 is a perspective view of a portion of one of the bars, Figs. 6 and 7 are sections on the lines 6-6 and 7-7, respectively, of Fig. 4, Fig. 8 is a vertical section showing a method of arranging the units in a battery.

In the present embodiment of the invention the improved heater and drier is shown in connection with the delivery end of a Fourdrinier machine indicated at 1, the web 2 of paper passing from the machine to the drier. The improved drier is composed of similar units, any number of which may be used, as for instance two being shown in Figure 1, and the paper is dried in a continuous operation, without checking the movement of the web, and with a minimum of travel of the web. Furthermore the web is supported and tensioned throughout its travel, so that it will dry uniformly, and without warping or bending. Each unit of the improved heater includes an open top boxlike casing, composed of a bottom 3, end walls 4, and side walls 5, the said casing being of any suitable material, as for instance sheet metal as shown. The upper edges of the side walls of the casing arch from end to end of the casing, being of greatest height at their center, and decreasing in height towards their ends. The side walls extend above the ends at the ends of the side walls, as shown in Figure 2, and each side wall is inwardly flanged at its upper edge, as shown at 6. Rollers 7 are journaled transversely of the top of the casing, the peripheral surface of the rollers being just below the flanges 6, and each roller has a shaft 8 whose ends extend through openings in the side walls of the casing, and are journaled in bearings 9 on a suitable frame 10 which supports the casing. A pair of rollers 11-11^a is journaled at the ends of the casing, one member 11 of each pair being near the top of the end, and the other member 11^a of each pair being below the bottom 3 of the casing and extending outwardly beyond the end of the casing. A roller 12 is journaled beneath the casing at the center thereof and a tension roller 13 is arranged between each roller 11^a and the roller 12. The tension roller 13 is journaled in a pair of arms 14, which are

pivoted at 15, to the frame 10, and weights 16 may be connected with the arms to secure the proper tension.

The rollers 7, 11, 11^a and 12 support an endless belt 17 of flexible foraminous material, in such manner that one run of the belt is at the open top of the casing, and closes the said top. The rollers 7 are arranged to support the said belt just below the flanges 6, and the web 2 rests upon the said run of the belt, and is supported thereby. The edges of the run of the belt and the edges of the web are beneath the flanges 6. The rollers 11, 11^a, 12 and 13 have end flanges as shown in Figure 2, for retaining the belt 17 in proper position with respect to the flanges 6, and to prevent lateral displacement thereof.

The endless belt 17, is as before stated of flexible foraminous material, and it is of such construction that the heated air may circulate freely through the same from every direction, both vertically from the heaters to the web, or laterally from the sides. A preferable material for the belt is wire cloth, as shown in Figure 4. This material provides a support for the web, which will engage it at restricted points relatively close set, and will permit a maximum circulation of heated air. The heating units are supported in the casing below the web, and each unit as shown more particularly in Figure 3, is composed of a pair of insulated members 18 circular in cross-section, and having a longitudinally extending groove 19 which is engaged by the edge of a supporting plate 20. The heating wire 21 is wound upon these members in spiral form, and the members are grooved to hold the coils of the wire in spaced relation, as clearly shown in Figure 3. Each of the plates 20 is provided at one end with a longitudinally extending notch 21, and at the other with a hook 22. Pairs of arms 23 are secured to the side walls of the casing, the members of each pair being secured to opposite side walls and extending toward each other, and being in register, and each arm 23 carries at its inner end a bolt 24. One of these bolts is engaged with the notch 21 of a plate, and the other bolt is engaged by the hook 22. When the nuts of the bolts are tightened, the plate is clamped to the arms, and the heater is supported spaced above the bottom of the casing, and below the upper run of the belt 17. The terminals of the heating wires 21 of the units may be connected in any suitable manner to an electrical circuit, and as many units may be used as may be found advisable.

Between the Fourdrinier machine, and between each of the units of the heater, the web is passed between tensioning rollers indicated at 25. A set of these rollers is arranged between each pair of adjacent units,

between the first unit and the Fourdrinier machine, and between the last unit and the receiving mechanism for the dried web. The rollers are arranged with their axes in the same plane, and the web passes over the lateral rollers and beneath the central roller and is guided thereby.

In Figure 1 the units are shown as arranged in alignment. In Figure 5 they are shown superposed or one above the other. This arrangement is preferred in some cases, especially where there is a lack of space, since a battery of units occupies no more floor space than a single unit when arranged as shown in Figure 1. In the arrangement of Figure 8 the units indicated generally at 26 are supported one above the other on the frame 27. They are in all respects similar to the units shown in Figure 2, and the web passes over the topmost unit, downwardly at the right end of the frame, over the succeeding unit and downwardly at the left end of the frame to the third unit. A set of tension rollers 28 is arranged at each end of the frame, one set between the first and second units and the other between the second and third units. These rollers 28 correspond to the rollers 25, and the web passes between them in the same manner as it passes between the rollers 25. Another set of tension rollers 28 is arranged at the delivery end of the lowermost unit, and a set 30 is arranged at the receiving end of the topmost unit.

Draft openings may be provided in the side walls 5 of the heater box, and dampers 31 are provided for regulating the flow of air through the openings and through the box.

While not wishing to be bound by anything, it is my present opinion that the wire netting on which the web is supported, plays an important part in the advantageous results attained, partly by equalizing and distributing the heat after the principle of the miner's safety lamp and partly by forming pockets or cells in which air and steam are temporarily entrapped and so protect the web from the scorching effect of the electric heaters. By this apparatus the web can be subjected to temperatures far above those usually used in steam cylinder driers. The initial cost of the apparatus is lower than for steam drying, the space required is less, and there is often much convenience in using electrical energy for drying, particularly where water-power is plentiful and coal is scarce.

The netting which forms the belt which supports the web, is of a construction especially adapted for this purpose, in that it is so constituted that the portions which engage the belt are restricted portions, and they are relatively close set. Referring to Figures 4 to 7 inclusive, it will be seen that

the netting is composed of a series of bars 32 formed from wire or the like, bent into zigzag form, the alternate zigzags being offset laterally from the intermediate zigzags. 5 Thus the alternate zigzags of each bar lie in a different plane to the intermediate zigzags, and only the alternate zigzags engage the web. These bars are arranged in pairs, the members of each pair being connected 10 at their ends, and each bar is linked with the other member of the pair and with the adjacent bar of the adjacent pair. Thus there is formed extending diagonally of the web in one direction a series of ribs, spaced 15 apart from each other as will be seen from Figure 4. The ribs are not continuous, but are interrupted, as clearly shown in Figures 6 and 7, so that the web is engaged by relatively close set restricted portions of the belt. 20 There is provided thus a maximum of support, with a minimum of contact, and in addition the wide grooves between the ribs provide pockets for air and for steam, which form a non-conducting blanket, whose 25 constituent elements are constantly changing, because of the free circulation of air through the belt in every direction. Furthermore the belt is freely collapsible or contractable longitudinally of the web, while it is relatively 30 rigid transversely of the web, the bars 32 being arranged transversely of the web. This is of especial advantage where one of the elements, as for instance the web is relied upon to move the other, since the belt may, 35 contract freely longitudinally, that is in the direction of its movement, without wrinkling, humping or buckling. The bars of which it is composed merely slip closer alongside each other, and there is no wrinkling of the belt which would tend to bend the 40 paper web.

I claim:

1. A drier unit comprising an endless belt having a run thereof supported in arched 45 formation from end to end, and supported to move with a moving web of paper or the like to be dried, and heating means below the said run of the belt.

2. A drier unit comprising an endless belt 50 having a run thereof supported in arched formation from end to end, and supported to move with a moving web of paper or the like to be dried, and heating means below the said run of the belt, the belt being of 55 foraminous material.

3. A drier unit comprising an endless belt having a run thereof supported in arched 60 formation from end to end, and supported to move with a moving web of paper or the like to be dried, and heating means below the said run of the belt, the belt engaging the web with restricted portions thereof relatively close set for the purpose specified.

4. A drier unit comprising an endless belt 65 having a run thereof supported in arched

formation from end to end, and supported to move with a moving web of paper or the like to be dried, and heating means below the said run of the belt, the belt being previous to air in all directions.

70

5. A drier unit comprising an endless belt having a run thereof supported in arched formation from end to end, and supported to move with a moving web of paper or the like to be dried, and heating means below 75 the said run of the belt, the belt being previous to air in all directions, and the heating means being electrically controlled.

6. A drier unit comprising a casing having an open top, heating means within the 80 casing, and a support for the web of paper or the like to be dried at the open top of the casing and mounted to travel with a moving web of paper or the like to be dried.

7. A drier unit comprising a casing having an open top, heating means within the 85 casing, and a support for the web of paper at the open top of the casing and mounted to travel with a moving web of paper or the like to be dried, the support being arched 90 longitudinally for the purpose specified.

8. A drier unit comprising a casing having an open top, heating means within the casing, and a support for the web of paper or the like to be dried at the open top of 95 the casing and mounted to travel with the moving web of paper, the support engaging the web with restricted portions thereof relatively close set.

9. A drier unit comprising a casing having an open top, heating means within the casing, and a support for the web of paper or the like to be dried at the open top of the casing and mounted to travel with the moving web of paper, the support being arched 100 longitudinally, and engaging the web with restricted portions thereof relatively close set.

10. A drier unit comprising a casing having an open top, heating means within the 110 casing, and a support for the web of paper or the like to be dried at the open top of the casing and mounted to travel with the moving web, said support being of flexible foraminous material.

115

11. A drier unit comprising a casing having an open top, heating means within the casing, and a support for the web of paper or the like to be dried at the open top of the casing and mounted to travel with the 120 moving web of paper, the support being previous to air in all directions.

12. A drier unit comprising a casing having an open top, heating means within the casing, and an endless belt having a run 125 thereof supported at the open top of the casing for engagement by the web of paper or other material to be dried to support said web and to be moved thereby.

13. A drier unit comprising a casing hav-

130

4

ing an open top, heating means within the casing, and an endless belt having a run thereof supported at the open top of the casing for engagement by the web of paper or other material to be dried to support said web and to be moved therewith, and means in connection with the supporting means for constraining the said run of the belt to assume an arched formation longitudinally 10 of the casing.

14. A drier unit comprising a casing having an open top, heating means within the casing, and an endless belt having a run thereof supported at the open top of the casing for engagement by the web of paper or other material to be dried to support said web and to be moved therewith, the belt being pervious to air in all directions.

15. A drier unit comprising a casing having an open top, heating means within the casing, and an endless belt having a run thereof supported at the open top of the casing for engagement by the web of paper or other material to be dried to support said web and to be moved therewith, the heating means comprising a series of electrically controlled units.

16. A drier unit comprising a casing having an open top, heating means within the casing, and an endless belt having a run thereof supported at the open top of the casing for engagement by the web of paper or other material to be dried to support said web and to be moved therewith, the heating

means comprising a series of electrically 35 controlled units, the side walls of the casing having inwardly extending arms, and the units being detachably connected with the arms and extending transversely of the cas- 40

ing.

17. A drier unit comprising a casing having an open top, heating means within the casing, and an endless belt having a run thereof supported at the open top of the casing for engagement by the web of paper 45 or other material to be dried to support said web and to be moved therewith, the supporting means being arranged to arch the belt longitudinally on the said upper run, and the side walls of the casing having inwardly extending flanges engaging above the said run.

18. A drier unit comprising a casing, having an open top, means at the open top for supporting and guiding the web of paper 55 or the like to be dried and freely movable beneath the web, said means being arranged in arched formation longitudinally of the casing, and heating means within the casing.

19. A drier unit comprising a casing, having an open top, means at the open top for supporting and guiding the web of paper or the like to be dried, said means being mounted to travel with the web, and heating means within the casing.

In testimony whereof I affix my signature.

FREDERIC PAYSON REED.

Certificate of Correction.

It is hereby certified that in Letters Patent No. 1,432,736, granted October 17, 1922, upon the application of Frederic Payson Reed, of East Orange, New Jersey, for an improvement in "Driers," errors appear in the printed specification requiring correction as follows: Page 3, line 31, for the word "web" read *belt*; same page, lines 97, 105, and 121, claims 8, 9, and 11, strike out the words "of paper"; and that the said Letters Patent should be read with these corrections therein that the same may conform to the record of the case in the Patent Office.

Signed and sealed this 28th day of November, A. D., 1922.

[**SEAL.**]

KARL FENNING,

Acting Commissioner of Patents.
